UNITED STATES PATENT OFFICE.

AUGUST SNYDER AND JOSEPH B. CONNOLLY, OF PITTSBURG, PENNSYLVANIA, ASSIGNORS TO AUGUST SNYDER, OF PITTSBURG, PENNSYLVANIA.

CONDENSER.

SPECIFICATION forming part of Letters Patent No. 723,324, dated March 24, 1903.

Application filed October 8, 1901. Serial No. 77,964. (No model.)

To all whom it may concern:

Be it known that we, AUGUST SNYDER and JOSEPH B. CONNOLLY, citizens of the United States, residing at Pittsburg, in the county 5 of Allegheny and State of Pennsylvania, have invented certain new and useful Improvements in Condensers; and we do hereby declare the following to be a full, clear, and exact description of the invention, such as 10 will enable others skilled in the art to which it appertains to make and use the same.

Our invention has relation to condensers of that class in which the exhaust from a steam-engine is brought into contact with a 15 stream of water in a condensing-chamber at the upper end of a stand-pipe, the condensed steam and water falling down the stand-pipe and tending to form a vacuum whereby the steam is forcibly sucked from the exhaust- 20 ports of the engine, thereby greatly increasing the efficiency of the engine. In apparatus of this class it has been found necessary to produce the best effect to draw off from the steam and water any air which may 25 be carried thereby into the condensing apparatus; and our invention has for its object the provision of novel means for condensing any steam or moisture which may be drawn off with the air, so as to prevent such steam 30 or moisture from entering the air-pump.

Our invention consists in the novel construction, combination, and arrangement of parts hereinafter described and claimed.

Referring to the accompanying drawing, 35 which is a vertical sectional view of a condenser constructed according to our invention, A designates the exhaust-pipe by means of which exhaust-steam is conveyed to the condenser from a steam-engine or other apparatus.

C designates the condensing-chamber, to which the pipe is connected by an elbow B.

D designates the water-delivery pipe receiving a supply of water from a suitable 45 water-elevating apparatus, such as a pump. The water-delivery pipe D is connected to an elbow J, that passes into the elbow B, the elbows J and B being preferably a single casting.

At the upper end of the water-delivery

pipe D an air-chamber K is arranged, and above the chamber K is a small supplementary chamber k, from which leads a pipe k' to the air-suction pipe M, the air passing on its way to said air-suction pipe through the 55 upper end of a condensing-chamber L. A downwardly-opening valve W is arranged between the chambers K and k, and the stem of the valve W has on its upper end a small upwardly-opening valve w, that leads to the 60 open air, while the lower end of the stem carries a float v.

The elbow J of the water-delivery pipe terminates within the condenser-chamber C in a funnel-shaped mouth N, and below the 65 mouth N is a suspended bell O, having an upturned lip o, the bell being suspended on a rod P, that has a screw-thread upon its upper end that works through a nut Q, beveled gears R S serving to turn the rod in the nut 70 and adjust the position of the bell. The bell O has a bushing T at its center through which passes the upturned end U of an air-pipe q, the purpose of pipe U being to draw off the air which accumulates beneath the 75 bell.

The condensing-chamber L is composed of concentric cylindrical walls l m, having between them a spiral passage L', through which the air passes on its way from the pipe U, 80 through which it is drawn from under the bell O. The exterior wall l of the condensing-chamber L is formed with a large number of radial fins or thin flanges l' l'', the purpose of which is to radiate and disburse as 85 quickly as possible the heat which will be communicated to the wall l by any steam that may be conveyed into the condensing-chamber L with the air. The inner wall m of the chamber L is preferably made as thin 90 as possible and integral with the spiral o', which forms the spiral passage for the air, and the interior wall m forms a straight passage m', that extends entirely through the chamber L and permits of a free flow of the 95 outer air, by means of which the heat is rapidly conveyed away from said interior wall m and from the spiral o'. A drain-pipe y leads from the bottom of the chamber L to the tail-pipe Y, and a trap W', that contains 100

a shield W^2 , which is fixed over the exit of the trap, is connected to the drain-pipe y by a branch y' .

Operation: The water from the water-supply pipe issuing from the elbow J through the funnel-mouth N falls upon the bell O and striking the lip o is spread and falling over the lip and down through the condensing-chamber C falls into the tail-pipe Y . The steam from the exhaust-pipe A , passing into the chamber C through elbow B , meets the water flowing from the funnel-mouth and which is spread out to the sides of the condenser-chamber C by the upturned lip of the bell O and is rapidly condensed, and the water of condensation falls into the tail-pipe Y . The air is separated from the water passing up the delivery-pipe D and passes into the air-chamber K , from which it is drawn off through valve W and thence to the top of the condensing-chamber L , through chamber k and pipe k' , and thence to the air-suction pipe M . Any air that may be brought into the condenser-chamber C with the steam or water will accumulate under the bell O and will be drawn from under the bell by the pipe U and passing through pipe q to the spiral passage L' and up through the latter to its top and thence to the air-suction pipe M . Any vapor which may be drawn from the condenser-chamber C into the supplementary air-cooled condensing-chamber L will be condensed in said chamber, and the resulting water of condensation will run down the spiral passage and be discharged into the tail-pipe Y by the drain-pipe y . If under any circumstances vapor or steam should escape condensation in the supplementary condensing-chamber L and pass over into the suction-pipe M , it will be condensed therein, and the resulting water of condensation will be received in the trap W' and drained off through branch y' to the drain-pipe y and thence to the tail-pipe Y . If through an excessive supply of the water should rise in the air-chamber K , the float v will rise with the water and close valve W , thus preventing the water from passing into the air-suction pipe. When the valve W is closed, the valve w will be opened and air admitted from outside, which will break the vacuum and cause the valve W to open and the water to sink in the supply-pipe.

Having described our invention, we claim—

1. In a condensing system, the combination with a condensing-chamber, a water-pipe leading into said chamber, a tail-pipe and an air-exhaust pipe leading from said chamber, of an air-cooling chamber having entrance and exit openings connected to said air-exhaust pipe and having its exterior surface ex-

posed to and wholly cooled by the outer air, substantially as described.

2. In a condensing system for condensing steam by direct contact with water, the combination with a condensing-chamber, a steam-pipe and a water-pipe leading thereinto and a tail-pipe and an air-exhaust pipe leading therefrom, of an air-cooling chamber connected to said air-exhaust pipe and formed with double walls and a central passage, the exterior surfaces of the outer wall and the central passage being exposed to the outer air so as to cool the air passing between the double walls wholly by radiation, substantially as described. 65 70 75

3. In a condensing system for condensing steam by direct contact with water, the combination with a condensing-chamber, a steam-pipe and a water-pipe leading thereinto and a tail-pipe and air-exhaust pipe leading therefrom, of an air-cooling chamber connected to said air-exhaust pipe and formed with double walls and a central passage, the exterior surface of the outer wall and the interior surface 80 85 of the central passage being exposed to and cooled wholly by the outer air and said air-cooling chamber being provided with a pipe leading to the said tail-pipe substantially as described. 90

4. In a condensing system for condensing steam by direct contact with water, the combination with a condensing-chamber, a steam-pipe and a water-pipe leading thereinto and a tail-pipe and an air-exhaust pipe leading 95 therefrom, of an air-cooling chamber located on a branch leading from said condensing-chamber to said air-exhaust pipe said air-cooling chamber being formed with double walls having a tortuous passage between said 100 walls for the passage of the air to be cooled, a free central opening and radiating projections on the exterior of its outer wall, the said outer wall and the central passage being exposed to and cooled wholly by the outer air, 105 substantially as described.

5. In a condensing system, the combination with a main condensing-chamber, a suction-pipe and pipe connections between said chamber and suction-pipe, of an air-cooler, on said 110 connections a drain-pipe from said air-cooler, a trap on the connection between said cooler and the suction-pipe and a drain from said trap.

In testimony whereof we have affixed our 115 signatures in presence of two witnesses.

AUGUST SNYDER.
JOSEPH B. CONNOLLY.
